CLAIM

The ornamental design for a disk casing punch tool, as shown and described.

DESCRIPTION

FIG. 1 is a perspective view of a punch tool incorporating the design;

FIG. 2 is a side elevational view of the design of FIG. 1, the left side and right side elevation having the same appearance;

FIG. 3 is a top plan view of the design of FIG. 1;

FIG. 4 is a bottom plan view of the design of FIG. 1;

FIG. 5 is a front elevational view of the design of FIG. 1;

FIG. 6 is a rear elevational view of the design of FIG. 1.

FIG. 7 is a perspective view of an alternative punch tool incorporating the design with a bottom cover.
